TITUS RUSSELL, OF ALBION, MICHIGAN

WARM AIR FURNACE

Application filed January 9, 1930. Serial No. 419,505.

The invention relates to improvements in warm air furnaces.

The objects of the invention are:

First, to simplify the construction of such a furnace and avoid the use of special radiator and radiator connections.

Second, to provide such a furnace with firepot and combustion chamber with direct smoke pipe connection.

10. Third, to provide such a structure in which the firepot is made up of vertical stave-like sections with special joint and retaining means to hold them in place.

15. Fourth, to provide in such a furnace an improved combustion chamber with stave-like sections with special means for retaining them in place.

20. Fifth, to provide a furnace so constructed with vertical radiating fins on the firepot and combustion chamber.

Sixth, to provide in such a structure an improved adjustable joint means whereby the same staves can be made use of for the manufacture of firepots of different diameters and 25 capacities.

Seventh, to provide such a structure with an improved spring retaining band or hoop.

Eighth, to provide an improved top or smoke collar structure for a sectional combustion chamber dome with improved packing joint therefor.

Ninth, to provide such a structure with an improved fuel feed neck.

Tenth, to provide such a structure with 35 improved water heater sections for both the firepot and the combustion chamber.

Objects relating to details and economies of my invention will appear from the description to follow. The invention is defined and 40 pointed out in the claims.

Preferred embodiments of my invention are illustrated in the accompanying drawings, in which:

Fig. 1 is a detail vertical central sectional elevation through the furnace firepot and combustion chamber and surrounding casing taken on line 1—1 of Figs. 2 and 3, the top of the casing and the lower part of the casing and ashpit being broken away.

Fig. 2 is a detail transverse sectional plan

view through the mid-portion of the firepot taken on line 2—2 of Figs. 1 and 10.

Fig. 3 is a detail sectional plan view through the combustion chamber of the furnace, taken on section line 3—3 of Fig. 1. 55

Fig. 4 is an enlarged detail horizontal sectional view on line 4—4 of Figs. 1 and 10 through a plurality of the firepot sections, showing the form of the joint therebetween and the relation of the radiating fins. 60

Fig. 5 is a detail perspective view of one of the stave-like sections of the firepot.

Fig. 6 is a perspective view of one of the stave-like sections of the combustion chamber. 65

Fig. 7 is a detailed vertical section through one of the hollow firepot staves on line 7—7 of Fig. 2 showing the water connections.

Fig. 8 is a detailed vertical section through one of the hollow combustion chamber staves 70 on line 8—8 of Fig. 3 showing the water connections.

Fig. 9 is an enlarged detail longitudinal section through one of the tie band yokes taken on line 9—9 of Fig. 1. 75

Fig. 10 is a detail vertical sectional view comparable to Fig. 1 showing a modification of the structure in which the firepot alone is made of sections, the combustion chamber and other parts of the furnace being of usual construction. 80

The parts will be identified by their numerals of reference which are the same in all the views.

1 is the ashpit or base casting of the furnace which may be provided with any usual grate such as the bar grate 2. 85

Supported on the base is the firepot 3 which is made up of stave-like sections 31. The lower ends of these staves are shouldered at 32 to form a joint with the groove in the base casting 1. The upper ends of the staves are likewise shouldered at 34 to form a joint with the combustion chamber above. 90

Vertically on each side of the firepot section is formed a joint groove 35 and disposed in the said vertical groove is a round rod 8 which is embedded in asbestos cement and makes a flexible and tight joint between the parts, yielding sufficiently to take care of the 95 100

expansion and enables the said stave-like sections to be used without any special fitting for firepots of different diameters within the usual limits of such structures.

5 Each section is provided with a plurality, here shown as three, vertical series of parallel heat radiating fins 33, these being in staggered relation so that the center fin is centrally disposed of the stave and is unobstructed on both sides, this fin being formed to receive the saddle for the clamping means which retains the staves together.

15 Around the firepot sections is disposed the retaining band 4. Between the band and each section is disposed a saddle 5 which is made up of an open ended box-like section on the bottom of which are formed a pair of vertical ribs 51, 52 which straddle the said center fin of the stave-like section 31. An 20 anti-friction roller 53 is disposed at each end of the saddle.

25 One of these saddles is provided for each segment of the firepot. They are clamped and retained together by the tie rod or band or hoop 4. The hoop 4 is made adjustable by the double lever means 6, 6 which are fulcrumed together at their inner ends at 61. The meeting ends of the band 4 are upturned at 41 and secured to the levers by suitable 30 bolts 42. The outer ends of the levers 6 are provided with a radiating bolt 62 having a spring 63 and an adjusting nut 64 for drawing the said levers together under strong spring pressure.

35 7 is the outer casing of the furnace which is suitably slotted at 71 to accommodate the adjusting lever 6. The bolt 62 and spring 63 are disposed outside of the casing so that they will not be exposed to injury by the 40 heat.

45 Towards the bottom and inside of each stave I cast inwardly-projecting upwardly-tapering ribs 36 which when disposed as seen in Fig. 4 form air passages around the base 50 of the firepot for the ready intake of air to maintain the combustion. All of these are so formed that they are in straight lines at right angles to the body part of the stave so that the series of fins and ribs and all parts can be very readily cast from patterns without use of cores.

55 When desired, one or more sections of the firepot can be enlarged and made hollow (see 7—A, Figs. 2 and 7), fittings and connections 60 being provided for the top and bottom thereof to circulate water therethrough for heating a range boiler or a radiator as desired.

65 In my preferred construction I make the combustion chamber of similar staves to those of the firepot.

70 When these firepot sections are assembled together, the shoulders 34 at the top form a groove for the joint to the combustion chamber above and on this groove I dispose and arrange a sectional combustion chamber also

made up of vertical segment-like staves 9. These are provided with a series of vertically disposed parallel radiating fins 91 on each section like the firepot only with the main portion at the top. Towards the bottom 70 there are centrally disposed fins projecting to receive a retaining band which is the same as that disposed and arranged around the firepot. The feed neck is especially supported and is taken care of by the casting of two of the sections 9 together as a single section 10 (see Fig. 3). The feed neck 11 is formed on and through the same, as seen also in Fig. 1, where the same appears in section with the feed door 12 at the front.

80 One or more staves of the combustion chamber may be hollow and be provided with water connections to a radiator or heating system as seen at 9—A in Figs. 3 and 8.

85 The clamping band is divided and secured by suitable lugs 111 to the oposite sides of the feed neck (see Fig. 3). This band is retained by a double lever structure precisely the same as the connection for the firepot below. A second band is preferably disposed around the combustion chamber engaging fins 91 towards the top, as seen particularly in Fig. 1, which is shown partially in Fig. 3 and partially broken away to show the lower band as well.

90 The combustion chamber staves are provided with inwardly projecting vertical fins 92 within the top which project into the path of the products of combustion when they are emerging from the said combustion chamber.

95 A smoke collar 13 of cast metal is provided with a pipe flange 131 at the top and double anular flanges 132, 133 around the bottom. These flanges 132, 133 are separated to form grooves 134 which receives the inwardly projecting upper ends of the staves 9 and the packing cement and the clamping rod or band 135. This rod is clamped in place by screw thread of any suitable means and wedges under the upper flange 133 thereby 110 forcing the lower flange 132 firmly up against the inner ends of the combustion chamber segments 9, clamping the cement and forming a tight joint both above and below the same.

115 The smoke pipe 14 shown in fragment leads out through the side of the casing 7 in any direction.

120 In Fig. 8 a modified form is shown in which a combustion chamber 15 of usual construction is provided and fitted onto the top of the firepot.

125 With my improved construction it will be readily understood that great economies are accomplished in the matter of manufacture. A single pattern for a firepot stave serves to make any size firepot within the range of requirements. A single pattern for a combustion chamber stave is sufficient for each size of combustion chamber. The joints between 130

the segments of the firepot being provided with round rods are very flexible and accommodate expansion and contraction and also for the adjustment necessary in clamping the parts together by the bands. This obtains also in the manufacture of the combustion chamber as the rods can be bent to form and fit into the groove joints between the staves of the combustion chamber.

19. The saddles for each section provide an anti-friction means for the clamping band but the expansion being even in all directions it is possible to produce the structure without the presence of the saddle although the saddles are of very great advantage.

With my improved furnace, if a stave or segment burns out, it can be readily replaced without replacing the whole firepot or combustion chamber. By forming the structure 20 in segments in this way, large fins are readily formed on each section because it is a matter of straight casting that can be made very smooth from patterns and present a large radiating surface for absorbing the heat from 25 the firepot and combustion chamber. This being so, it is not necessary to provide a radiator to insure the heat transfer as that is accomplished by the fins. This results in saving of the very large castings usual for radiators and it permits of a compact furnace casting, delivering the heated air very promptly to the rooms to be heated. The castings, because of this free circulation, remain clean and do not accumulate dust and soot and consequently remain in efficient condition for the transfer and delivery of the heat.

As pointed out, the firepot is available in any style of furnace. Also the combustion chamber can be superimposed on the regular design of firepot but these structures go especially well together and they lend themselves to a matter of combination hot air and hot water furnace.

I have shown my improvements in the form especially preferred by me. I desire to claim it in that specific form and also desire to claim it broadly as pointed out in the appended claims.

Having thus described my invention, what I claim as new and desire to secure by Letters Patent, is:

1. A furnace firepot made up of upright stave-like sections with joint shoulders at top and bottom, joint grooves on the sides of each of said staves, packing cement and round rods disposed in said joints, inwardly projecting vertical flanges at each side of the bottom of each stave to form air passages around the firepot, outwardly projecting vertical parallel heat radiating fins on each stave including a center fin which is unobstructed at each side, a combustion chamber made up of stave-like sections superimposed on the said firepot sections, each stave curved inwardly at the top and being provided with joint grooves

at each side and provided with a curved rod and asbestos packing cement in the joints, and each having outwardly projecting radiating fins on its outer surface including a center fin and an inwardly projecting radiating fin at the top, a smoke collar therefor with pipe flange at the top and laterally projecting spaced flanges at the bottom, forming an angular joint groove embracing the upper ends of said combustion chamber staves, 70 packing cement in said joint and a retaining compression ring in the said annular space above the ends of said staves, a clamping band around the said staves for both the firepot and combustion chamber, saddles for each 75 stave section comprising longitudinal box-like members with lugs for engaging the center fin of each stave section and with rollers towards each end on the outside for engagement by the clamping band for the said firepot and combustion chamber, a pair of levers pivoted and fulcrumed together at their inner ends connected to each of said clamping bands intermediate their ends, and a spring bolt for clamping the outer ends of said levers together.

2. A furnace firepot made up of upright stave-like sections with joint shoulders at top and bottom and with joint grooves at each side, outwardly projecting vertical parallel heat radiating fins on each stave including a center fin which is unobstructed at each side, inwardly projecting vertical flanges toward each side of the bottom of each stave to form inlet air passages around the firepot, 95 packing cement and round rods disposed in said joints between said staves, a clamping band around the said staves, a saddle for each stave section comprising a longitudinal box-like member with a lug for engaging the center fin of each stave section and with rollers towards each end on the outside for engagement by the clamping band, a pair of levers pivoted and fulcrumed together at their inner ends and connected intermediate their ends 100 to the ends of said clamping band, and a spring bolt for clamping the outer ends of said levers together.

3. A furnace firepot made up of upright stave-like sections with joint shoulders at top and bottom and with joint grooves at each side, outwardly projecting vertical parallel heat radiating fins on each stave including a center fin which is unobstructed at each side, inwardly projecting vertical flanges toward each side of the bottom of each stave to form inlet air passages around the firepot, packing between the grooves of said staves, a clamping band around the said staves, a saddle for each stave section comprising longitudinal 115 box-like member with a lug for engaging the center fin of each stave section and with rollers towards each end on the outside for engagement by the clamping band, a pair of levers pivoted and fulcrumed together at their 120

125

130

inner ends connected intermediate their ends to the ends of said clamping band, and a spring bolt for clamping the outer ends of said levers together.

4. A furnace firepot made up of upright stave-like sections with joint shoulders at top and bottom and with joint grooves at each side, outwardly projecting vertical parallel heat radiating fins on each stave including a center fin which is unobstructed at each side, inwardly projecting vertical flanges toward each side of the bottom of each stave to form inlet air passages around the firepot, packing between the grooves of said staves, a clamping band around the said staves, a pair of levers pivoted and fulcrumed together at their inner ends connected intermediate their ends to the ends of said clamping band, and a spring bolt for clamping the outer ends of said levers together.

5. A furnace firepot made up of upright stave-like sections with joint shoulders at top and bottom and with joint grooves at each side, outwardly projecting vertical parallel heat radiating fins on each stave including a center fin which is unobstructed at each side, packing between the grooves of said staves, a clamping band around the said staves, a saddle for each stave section comprising a longitudinal box-like member with a lug for engaging the center fin of each stave section and with rollers towards each end on the outside for engagement by the clamping band, a pair of levers pivoted and fulcrumed together at their inner ends connected intermediate their ends to the ends of said clamping band, and a spring bolt for clamping the outer ends of said levers together.

6. A furnace firepot made up of upright stave-like sections with joint shoulders at top and bottom and with joint grooves at each side, outwardly projecting vertical parallel heat radiating fins on each stave including a center fin which is unobstructed at each side, packing between the grooves of said staves, a clamping band around the said staves, a pair of levers pivoted and fulcrumed together at their inner ends connected intermediate their ends to the ends of said clamping band, and a spring bolt for clamping the outer ends of said levers together.

7. A furnace firepot made up of upright stave-like sections with joint shoulders at top and bottom and with joint grooves at each side, outwardly projecting vertical parallel heat radiating fins on each stave including a center fin which is unobstructed at each side, packing cement and round rods disposed in said joints between said staves, and a yielding clamping band around the said staves.

8. A furnace comprising a combustion chamber made up of separate stave-like segments with inturned upper ends clamped to

gether, a cast smoke collar at the top of said combustion chamber with a smoke pipe flange at the top, lateral flanges at the bottom of said collar forming an annular recess embracing the upper ends of said staves, packing cement disposed within the recess, and a clamping ring forced into the recess between said flanges and above the ends of the staves to force the smoke collar upward and compress the packing.

In witness whereof I have hereunto set my hand.

TITUS RUSSELL.
